CLAIM

The ornamental design for a smart toilet as shown and described.

DESCRIPTION

FIG. 1 is a perspective view of a first embodiment of a smart toilet showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the smart toilet of FIG. 1, where the smart toilet is in a configuration of use;

FIG. 10 is a perspective view of a second embodiment of the smart toilet;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is a perspective view of the smart toilet of FIG. 10, where the smart toilet is in a configuration of use.

The broken lines in the drawings depict portions of the smart toilet that form no part of the claimed design.
